UNITED STATES PATENT OFFICE.

JOHN O. NEIKIRK, OF LOMBARD, ILLINOIS, ASSIGNOR TO RODGER BALLAST CAR COMPANY, A CORPORATION OF MAINE.

DUMP-CAR.

1,242,226.

Specification of Letters Patent.

Patented Oct. 9, 1917.

Application filed July 15, 1916. Serial No. 109,568.

To all whom it may concern:

Be it known that I, JOHN O. NEIKIRK, a citizen of the United States, residing at Lombard, in the county of DuPage and State of Illinois, have invented certain new and useful Improvements in Dump-Cars, of which the following is a specification.

This invention relates to dump cars and its purpose is to provide an improved car 10 of this class having an improved arrangement of centrally discharging and laterally discharging dumping doors.

A particular object of the invention is to provide an improved dump car having a 15 central longitudinal hopper and comprising dumping doors which are arranged to permit the discharge of the contents of the car with greater facility than has hitherto been possible, as will be hereinafter more particularly pointed out.

The nature of my improvements and various objects of the invention will appear more clearly from the following specification, taken in connection with the accompanying drawings, in which one embodiment of the invention is illustrated.

In the drawings—

Figure 1 shows a partial side elevation of a railway car embodying the features of this 30 invention;

Fig. 2 shows a vertical transverse section taken on the line 2—2 of Fig. 1; and

Fig. 3 is a detail view of the ratchet mechanism for operating one of the shafts.

In the accompanying drawings the invention is illustrated in connection with a car in which the various parts are constructed of metal, but it will be understood that certain features of the invention may be applied to 35 cars embodying other features and materials of construction. In the drawings the running gear of the car is not shown, except the wheels 10, illustrated by dotted lines, which are shown supported upon the usual track rails 11, these features being shown for the purpose of illustrating the relative 40 location and arrangement of other parts of the car structure.

The car underframe comprises the longitudinal sills 12, which are spaced from the center line of the car and which extend longitudinally of the car between the bolsters 13. The car underframe further comprises the end sills 14 and side sills 15, all of which 45 are secured together by bolts or rivets ac-

cording to the usual method of construction. It will be seen that the side sills comprise relatively deep members 15^a, extending from the end sills past the bolsters, and the smaller angle beams 15^b which are secured 60 to the members 15^a and extend between the bolsters. Transverse sills 16, preferably of channel form, extend between the side sills. The sills 12 are located above the wheels 10 and rails 11 and each of said sills comprises an inverted channel beam 17 having secured thereto the plates 18, the lower and outer portions of which are directed downwardly to engage the flanges of the channel beam; and the inner and upper portions of which 65 are inwardly and downwardly turned, as shown at 18^a, to form flanges to be secured to the inner downwardly and inwardly inclined plates 19 which form the inner and upper walls of the longitudinal sills. The 70 lower portions of the plates 19 are bent downwardly as shown at 19^a and secured to the adjacent downwardly extending flanges of the channel beam, but the upper part of each of the plates 19 extends upwardly beyond the adjacent plate 18, as clearly shown, 75 for instance, in Fig. 2. These parts which form the sills 12 are suitably secured together by rivets or the like, and then are secured to the bolsters 13 by suitable angle 80 plates or other means, as shown, for instance, in Fig. 2. The channel beams 17 which form the lower walls of the sills 12 terminate at each end adjacent the innermost wheels of the car truck, as shown at 85 17^a, in order to provide suitable clearance for the uppermost parts of the peripheries of the wheels, and the other members of the longitudinal sills are reinforced from these 90 points to the bolsters 13 by means of the angle members 20. The bolsters 13 are of 95 composite metal construction as shown, and they extend upwardly from the sills 12 and side sills to the downwardly and inwardly inclined end walls 21 of the car. These end 100 walls are supported by the bolsters and also by the trusses or stakes 22 and 23 which extend upwardly from the side sills and end sills of the car.

The superstructure of the car comprises 105 the side stakes 24, which are secured to the side sills and the transverse sills of the car and extend upwardly therefrom, having secured thereto the vertical side walls 25 which are formed of metal plates, or the 110

like, riveted or otherwise secured to the side stakes and reinforced along their upper edges by the angle bars 25^a. These side walls 25 terminate above the underframe of the car, as clearly shown in the drawings, having inwardly directed angle plates 25^b secured to the lower edges thereof. The side walls are reinforced between the side stakes by vertically extending angle bars 26, which are riveted to the plates 25 and have their inwardly directed, oppositely disposed flanges connected to the transversely extending braces 25^c. Side dumping doors 27, of composite metal construction, are attached to the lower edges of these side walls between adjacent side stakes by means of hinges 27^a. These side dumping doors 27, when in normal closed positions, are inclined downwardly and inwardly so that their uppermost surfaces form continuations of the upper surfaces of the metal plates 19 which form the upper and inner sides of the longitudinal sills 12, the inner and lower edges of the doors being arranged to terminate adjacent the edges of the plates 19 so that a tight closure is formed. Z-bars or other suitable shapes 28 are attached to the inner and lower edges of the doors 27 and the lower flanges 28^a of these plates have secured thereto the chains 29 which are wound upon the operating shafts 30 and secured thereto by eye-bolts 30^a. These shafts 30 are mounted in suitable bearings carried by the center sills and other parts of the car underframe, and they extend longitudinally to the end of the car. Each of the plates 19 has secured thereto an inverted angle iron member 31 which overlies the adjacent longitudinally extending shaft 30 and which has a flange lying parallel to the web of the adjacent plate 28 when the dumping doors are in closed position. Supporting members 32, preferably of angle iron form, are attached to the upper sides of the sills 12 and extend upwardly and outwardly to the side stakes 24, forming stops for the doors 27, and closing the spaces between adjacent doors when the latter are moved to closed positions by the operation of winding the chains 29 upon the shafts 30 which form drums therefor. Downwardly and inwardly inclined plates 33, lying in the same planes as the doors 27 when the latter are in closed positions, extend from the inclined end walls 21 to the adjacent doors 27 and from the side walls 25 to the longitudinal sills, thus forming parts of the hopper at the ends of the car. Between the sills 12 there is formed the lower portion of the central longitudinal hopper which comprises the downwardly and inwardly inclined floor section 35 and the similarly inclined dumping doors 36, the floor section 35 being connected at its upper edge to the adjacent sill 12 and being

supported at its lower edge by the supporting members 37, which extend upwardly and are secured to the transverse sills 16 of the car. The centrally discharging dumping doors 36 are hinged at their upper edges to the adjacent longitudinal sill 12 by means of hinges 38, and the lower portions thereof are provided with brackets 39 which are connected by means of eye-bolts 40 to the chains 41 which extend around the lower meeting edges of the dumping doors 36 and the floor section 35 and thence upwardly beneath the floor section 35 to the operating shaft 44 upon which the chains are wound, and to which they are secured by eye-bolts 45. The shaft 44 is mounted on suitable bearings 46 carried by the adjacent longitudinal sill 12 and other parts of the car structure, and it extends longitudinally of the car to the end sill 14. The operating shaft 44 and the operating shafts 30 are operated by means of suitable lever and ratchet mechanism 47, which may be of the form shown in Fig. 3, for instance, comprising a lever 48 mounted on the rotatable operating shaft, a ratchet 49, and an oscillating pallet 50 mounted in a bracket 51 and guide 52 and having a securing cam 53. The members 51 and 52 may be attached to a plate 54 carried by the end sill 14. 95

It will be seen that by means of the foregoing construction a car is provided having a hopper bottom which comprises the downwardly and inwardly inclined end walls 21, the downwardly and inwardly inclined upper or side dumping doors 27, the downwardly and inwardly inclined inner walls of the longitudinal sills 12, and the downwardly and inwardly inclined floor sections and central dumping doors 35 and 36, respectively. This car, by reason of the above described arrangement of doors, has the advantage that it permits the discharge of the contents of the car centrally between the rails and also at the sides of the car outside the rails. 100 105 110

It will be noted that the discharge of the load centrally and at the sides may be made simultaneously, if so desired, so that with the car as hereinbefore described it is possible to discharge all of the load centrally between the rails, to discharge all of the load, a part between the rails, and a part at either or both sides of the car, or substantially the whole load may be discharged at the sides. It is oftentimes desirable in ballast and construction work to discharge more material at one side of the car than at the other, as, for example, when ballasting a double track road, it sometimes happens that it is desirable to discharge more material at the side of the outer rail than between the inner rails of the double track. So, too, in construction work in filling embankments it is often desirable to deposit 115 120 125 130

the greater part of the load at one side or the other of the track. All of these functions are performed by the car arranged as hereinbefore described.

5 Although I have shown and described a particular embodiment of the invention, it will be understood that it may be constructed in various other forms without departing from the scope thereof as defined in 10 the appended claims.

I claim:

15 1. A car having a stationary central longitudinal hopper, the sides of which are inclined downwardly and inwardly from the sides of the car, a hinged bottom door, and doors above said hopper hinged at their upper edges so as to swing outwardly, said doors forming when in closed position a portion of the hopper sides.

20 2. A car having a stationary longitudinal hopper the sides of which are inclined downwardly and inwardly from the sides of the car, a hinged bottom door, and doors above said hopper hinged at their upper 25 edges and arranged to form a portion of the hopper sides when in closed position and to swing outward to discharge at the sides of the car.

30 3. A car having a stationary longitudinal hopper with inwardly and downwardly inclined sides, a door for permitting downward discharge from the hopper, and doors above said hopper hinged at their upper edges for swinging out to discharge at the 35 sides of the car and arranged to occupy inclined positions and form continuations of the sides of the hopper when in closed position.

40 4. A car having a stationary longitudinal hopper with inwardly and downwardly inclined sides, a hinged bottom door for the hopper, and doors above said hopper hinged at their upper edges and arranged to swing

in and close to occupy inclined positions in continuation of the sides of the hopper, and 45 to swing out to discharge the contents of the car at the sides.

5 A car having a longitudinal hopper with inwardly and downwardly inclined sides, a hinged bottom door for the hopper, and upper doors hinged at their upper edges to the sides of the car and arranged to occupy inwardly and downwardly inclined positions in substantially the same planes as the sides of the hopper when 55 closed, and to swing outward when opened for discharging the contents of the car at the sides, said side discharging doors being operable independently of the bottom discharging doors.

6 A car of the class described having its body portion forming a hopper whose apex extends centrally and longitudinally of the car, said hopper being provided with lower doors closing the hopper at the apex and 65 with upper doors hinged at their upper edges above the fixed side portions of the hopper, said upper and lower doors forming when closed a part of the sides of the hopper.

7 A car of the class described having its body portion forming a hopper with its apex arranged centrally and longitudinally of the car, lower doors closing the apex of the hopper, and doors in the sides of the 75 hopper above the fixed portions thereof, said doors in the sides of the hopper being supported at their upper edges to swing outwardly.

In testimony whereof, I have subscribed 80 my name.

JOHN O. NEIKIRK.
